UNITED STATES PATENT OFFICE.

MAURICE FORCOZ, OF STRATFORD, CONNECTICUT.

WINDOW-SCREEN.

1,335,573.

Specification of Letters Patent. Patented Mar. 30, 1920.

Application filed September 23, 1916. Serial No. 121,846.

To all whom it may concern:

Be it known that I, MAURICE FORCOZ, a citizen of France, residing at Stratford, in the county of Fairfield and State of Connecticut, have invented certain new and useful Improvements in Window-Screens, of which the following is a specification.

This invention relates generally to window screens, and particularly to that type of screens which raise and lower as the sliding sash is opened or closed.

The primary object of the invention is to provide a screen of this character which is of simple and inexpensive construction, which is composed of but few readily assembled parts, all so constructed and arranged as to preclude the possibility of wear, breakage or derangement of the same, which is capable of being easily installed, which will operate perfectly when the window sash is moved, and which may be readily detached from the sash when required.

A further object of the invention is to provide a screening device of this character provided with improved tensioning means, whereby the mesh fabric is at all times maintained in proper position and is insured against buckling or wrinkling.

A still further object of the invention is to provide a screen of the roll type for use in connection with window frames having sliding sashes, and wherein the screen fabric is tightly and compactly rolled when the window is closed, which does not prove an unsightly attachment, but which will prove thoroughly efficient in the attainment of the ends for which it is designed.

With these objects in view, together with others which will appear as the description proceeds, the invention resides in the novel formation, combination and arrangement of parts, all as will be described more fully hereinafter, illustrated in the drawings, and particularly pointed out in the claim.

45 In the drawings:—

Figure 1 is a view illustrating a preferred form of the invention;

Fig. 2 is a vertical sectional view taken on line 5—5 of Fig. 1;

50 Fig. 3 is a fragmentary vertical sectional view illustrating a modified form of roll screen;

Fig. 4 is a fragmental sectional plan view taken on line 8—8 of Fig. 1.

Referring now to the drawings, and particularly to Figs. 1 and 2, 10 indicates a conventional form of window frame, within which the upper and lower sliding sashes 11 and 12 are mounted in the usual well known manner.

60 In this form of the device, the screen fabric, indicated at 20, is wound upon a roller 21 mounted for rotation in suitable brackets 22 at the base of the window sill. The screening is of a width to closely fit 65 between the vertical side members of the frame, and metallic guides 23 are secured upon the inner faces of the said vertical members for the reception of the lateral edges of the screen fabric. The outer or free 70 end of the fabric is provided with a reinforcing strip 24, by means of which the screen end may be secured to the lower cross stile of the lower window sash, screws or 75 nails 25 being employed to establish the connection. The strip 24 may also be provided with finger grips 26 whereby the sash may be readily manipulated.

76 The roller 21 carries a pulley 27 at each end, to each of which is connected one end 80 of a cord 28. These cords 28 extend upwardly close to the vertical members of the frame 10, and pass over pulleys 29 arranged at the upper end of the frame. The cords then pass downwardly, and are connected 85 to the vertical stiles of the sash 12 by contractile springs 30. Each of the guides 23 is provided with a hook 31, to which the springs 30 may be connected when it is desired to render the screen and its mechanism 90 inoperative. A removable casing 40 is attached to the window frame and incloses the screen roller as shown.

95 From this description it is apparent that as the sash 12 is raised the screen fabric 20 will be unrolled from its roller, while opposite movement of the sash will, by operation of the cords 28, cause the screen fabric to wind upon the roller 21. By means of the springs 30, it is obvious that sufficient tension is produced in the screen fabric to maintain the same properly stretched and against buckling, and by arranging pulleys and springs at each side of the screen fabric,

the latter is maintained evenly tensioned throughout its entire width, whereby tearing or straining of the mesh fabric is obviated.

- In Fig. 3 of the drawings, there is shown 5 a further modified form of the invention, wherein the roller 21 is rotatably mounted in its brackets 22 within the casing forming the lower sill of the frame. In this form of the invention, an opening 35 would be made 10 in the window sill to permit of the passage therethrough of the screen fabric and operating cords. In this instance, the screen rollers are arranged within the hollow sill at 15 the time of the erection of the house, or at the time of the construction of the frame, and the guide members are also assembled upon the frame at this time to cover the edges of the screen fabric during its raising and lowering movements.
- 20 While the present illustration is that of the preferred embodiment of the invention, it is obvious that minor changes in the details of construction and arrangement of parts may be resorted to, if desired, without 25 departing from the spirit of the invention or

exceeding the scope of the claim, and the right to make such variation in construction is hereby reserved.

What is claimed is:

In a window screen having a pair of 30 guides, a sheet of foraminous material mounted in said guides, a roller having one end of the foraminous material wound thereabout, a pulley at each end of the roller, a casing surrounding said roller, a pair of 35 flexible elements each having one end secured to one of the pulleys, a second pair of pulleys at the upper end of the frame around which the opposite ends of the flexible elements pass, the combination of a pair of 40 coiled springs connected at one of their ends to the flexible elements and at their other end to the window sash whereby to tighten the foraminous material at all times.

In testimony whereof I affix my signature 45 in presence of two witnesses.

MAURICE FORCOZ.
